UNITED STATES PATENT OFFICE

2,422,860

VACUUM CLEANER

Arthur W. Seyfried, Racine, Wis., assignor to
Scovill Manufacturing Company, Waterbury,
Conn., a corporation of Connecticut

Application March 7, 1945, Serial No. 581,423

6 Claims. (Cl. 230—55)

1

This invention relates to tank type vacuum cleaners and particularly to means located between the fan and motor units for controlling air currents leaving the fan and directing them radially inwardly and then axially through the center of the motor for the purpose of maintaining low armature temperature in the motor.

My invention comprises a compact, integrally cast unit consisting of a baffle plate, a bearing support and a plurality of vanes on the baffle plate, located between the fan and motor units, and provided with means for connecting the casting to the motor housing and thereby also connecting part of the fan housing to the said motor housing.

The vanes employed in my invention are located on that face of the baffle plate adjacent the motor, and said vanes are radially disposed and straight beginning at the central bearing support for a distance constituting about two-thirds of their length, the remaining one-third of said vanes being curved and terminating near the peripheral edge of the baffle plate.

Experiments have proven that vanes, regardless of whether they are straight or curved, without a baffle plate between the fan and said vanes, do not serve to direct the air currents as required for cooling the motor. Further, these experiments have shown that straight vanes radiating from the axial center, and mounted on a baffle plate, have the effect of abruptly stopping the rotational direction of the air leaving the fans and directing the air through the center of the motor. Curved vanes have the effect of producing a higher vacuum and gradually changing the direction of the air leaving the fans. By using vanes curved throughout their length, the armature temperature is higher because the air is not directed through the center of the motor.

By providing the baffle plate with a plurality of vanes formed as herein shown and described, said vanes extending radially from the center and ending in a curved portion near the peripheral edge of the baffle plate, I obtain the advantageous results of both the straight and the curved vanes not heretofore obtained by any other form of vane nor by either straight or curved vanes.

In that embodiment of the invention which I have chosen to illustrate in the drawings:

Fig. 1 is a longitudinal vertical sectional view of part of a tank type vacuum cleaner, namely: that part comprising the fan and motor units and the exhaust end of the housing.

Fig. 2 is a transverse sectional view taken in 55

2

the plane of the line 2—2 of Fig. 1, looking in the direction indicated by the arrows.

Fig. 3 is a fragmentary transverse sectional view taken in the plane of the line 3—3 of Fig. 1, looking in the direction indicated by the arrows.

The cleaner housing comprises a cylindrical body 10 having an offset portion 11 of decreased diameter whereby a circumferential shoulder 12 is formed inwardly of the end of the body 10. The end is defined by a formed flange 13 extending circumferentially of the body. At the end of the body 10 is an outer end bell or hood 14 and an inner bell or cap 15 provided with openings 16. The cap 15 has a member 17 arranged to abut the flange 13 and is welded thereto. The center of the outer hood 14 is open; the opening being defined by the inwardly directed flange 18. The hood 14 is removably mounted on the housing 10 by any suitable means, not shown.

Spaced radially from the housing 10 is an inner casing which comprises members 19, 20 and 21 for housing the fan and motor units.

The parts 19 and 20 are cup shaped. The member 19 has a bowl portion 22 which is slightly enlarged to fit over the portion 23 of the inner cup member 20. Said portion 23 terminates in an annular, inwardly bent flange 24 which engages the face of a ring 25 which is integral with the motor housing member 21, and abuts a shoulder formed by the flange 26 on said member 21. Toward the exhaust end of the cleaner, the housing member 21 is connected by straps 27 to a concentric internally screw threaded member 28.

The fan and motor housing comprising the aforementioned parts 19, 20 and 21, together with the parts 27 and 28, are resiliently mounted in the outer casing 10 by means of a resilient ring 29 which engages the portion 23 of the housing 20 and abuts the inner surface of the shoulder 12 of the casing 10. The motor-fan unit as a whole is drawn toward the exhaust end of the housing by means of the headed screw 30 which is screwed into the member 28 and bears on the plate 31 and resilient collar 32, the latter bearing on the flat end portion 33 of the hood 15, thus causing the unit to bear against the resilient ring 29.

The motor is indicated as a whole at 34 and its shaft at 35. The shaft 35 is mounted in bearings 36 and 37, the latter being supported in the member 28. The fan shaft 38 is integral with the motor shaft 35 and is rotatably jour-

nalled in the member 38. The fan assembly, including a spacer 38', is held on the shaft by the nut 39. Fans 40 and 41 are separated by the stationary disc 42 and the base portion of the cup shaped member 20 to which it is connected. The housing 20 is centrally apertured, the opening being approximately one and three quarters inches to allow the free passage of air adjacent the spacer 38', whereas the baffle plate or disc 42 is apertured very closely to the fan spacer so as to allow about $1/64$ inch clearance.

Between the fan 41 and the motor 34 is an integrally formed casting comprising the concentric bearing support 43, baffle plate 44 and vanes 45. The vanes 45 extend radially from the bearing support 43 for a distance constituting about two thirds of their length and then extend in a curved direction to the circumferential edge 46 of the baffle plate 44. At the inner or axial portion, the vanes 45 are approximately as wide as the thickness of the bearing support 43 and become gradually wider toward their outer edges, as shown in Fig. 1.

The baffle plate 44 is formed with a plurality of sleeves 47 and is countersunk as indicated at 48 for the reception of screw threaded bolts 49 which extend through said sleeves 47 and the ring 25 on the housing member 21, thereby rigidly connecting the baffle plate 44 to said motor housing 21. The bolts 49 also extend through the flange 24 of the housing member 20 and thus connect that housing member to the adjacent motor housing 21, and make a rigid unit of the fan and motor housings and their contents.

Also formed on the baffle plate 44 are two or more sleeves 50 for the reception of screws 51 which extend through the plate 44 into the motor and hold the field coils in place.

The vanes 45 operate in a space located between the baffle plate 44 on the left hand side, and the motor 34 and part 24 of the fan housing parallel with the baffle plate on the right hand side, as shown in Fig. 1. The vanes act on the air currents after they have passed the baffle plate edge 46; then the curved portions engage the air currents and gradually change the rotational, axially directed air to radially inwardly directed currents, and finally the straight portions direct said currents axially through the center of the motor and thence outwardly between the bells 14 and 15 to the exhaust opening.

The making of the bearing support 43, baffle plate 44 and vanes 45 in one integral casting provides an efficient, inexpensive and compact unit which controls the air currents leaving the fan for the purpose of maintaining low armature temperature. The means provided for connecting the casting to the motor housing 21 also serves to connect the housing member 20 to said housing 21, thereby minimizing the number of parts required and producing a rigid and compact enclosed fan and motor unit.

The vanes 45 and their form and arrangement relatively to the baffle plate 44 serve to control the air currents leaving the fan in such manner as to direct them radially inwardly toward the motor shaft and then axially through the center of the motor, resulting in higher efficiency and low armature temperature.

Changes may be made in details of construction without departing from the scope of my invention as set forth in the appended claims.

I claim:

1. A vacuum cleaner comprising a fan unit, a motor, housings for containing said fan unit and

motor, said fan unit and motor having a shaft mounted axially in said housings, a bearing for the shaft between the fan unit and motor, and means for controlling the directions of the air currents leaving the fan, said means being an integrally formed unit comprising a bearing support for the shaft bearing, a baffle plate extending radially from the bearing support, the peripheral edge of the baffle plate being spaced from the fan housing and providing a passageway for air between said plate edge and the housing, and a plurality of vanes on that face of the baffle plate adjacent the motor between said bearing support and the peripheral edge of the plate, said vanes engaging air currents leaving the fan after they have passed between the baffle plate edge and the fan housing, and directing said currents inwardly toward the motor shaft and then axially through the motor.

2. The vacuum cleaner defined by claim 1, in which the integrally formed unit for controlling the air currents includes a plurality of sleeve members formed on the baffle plate, extending axially between the plate and the motor housing, and in which the said unit is connected to the motor housing by screw bolts extending through the baffle plate, sleeve members and said motor housing.

3. The vacuum cleaner defined by claim 1, in which the integrally formed unit for controlling the air currents includes a plurality of sleeve members formed on the baffle plate, and in which said unit is located in the fan housing and is connected to the motor housing by connecting means which extend through said baffle plate, sleeve members, the fan housing and said motor housing and thereby also connect the fan housing to the motor housing.

4. A vacuum cleaner comprising a fan unit, a motor, housings for containing said fan unit and motor, the fan housing comprising two cup shaped members one of which is engaged by the bowl portion of the other and its base provides a baffle member between two fans, and means for controlling the directions of the air currents leaving the fan unit, said means being an integrally formed baffle plate and vanes on that face adjacent the motor, located in the fan housing, between the fan and motor, sleeve members on the baffle plate extending in axial directions to and abutting the motor housing, and means extending through the baffle plate, sleeve members, one of the cup shaped members of the fan housing and said motor housing whereby the baffle plate is connected to the motor housing and the fan housing and motor housing are also connected together.

5. The vacuum cleaner defined by claim 1, in which the motor includes conventional field coils and the baffle plate is provided with openings and screws which extend through the openings in the plate and bear against the field coils and thereby hold said field coils in position.

6. A vacuum cleaner comprising a fan unit, a motor, housings for said fan unit and motor, said fan unit and motor having a shaft mounted axially in said housings, and means for controlling the directions of the air currents leaving the fan unit, said means comprising a baffle plate stationary mounted between the fan unit and the motor, the peripheral edge of the baffle plate being spaced from the fan housing and providing a passageway for air between said plate edge and the housing, and a plurality of vanes on that face of the baffle plate adjacent the motor, said vanes extending radially from the axial portion of the

baffle plate for a distance approximately two-thirds of their length and in a curved direction between said radially extending portions and the peripheral edge of the baffle plate, said curved portions of the vanes engaging the air currents from the fan and directing them inwardly after they have passed between the baffle plate edge and fan housing, and said radial portions of the vanes serving to abruptly halt the rotational direction of said air currents and to direct them axially through the center of the motor, said motor shaft having a bearing and said baffle plate and vanes being integrally formed, with the axial portion of the baffle plate thickened and apertured to provide a support for said motor shaft bearing.
